UNITED STATES PATENT OFFICE.

WILLIAM B. KING, OF LEAKSVILLE, NORTH CAROLINA.

DESIGN FOR A COMBINATION BENCH AND WARDROBE.

Application filed July 12, 1927. Serial No. 22,737. Term of patent 7 years.

To all whom it may concern:

Be it known that I, WILLIAM B. KING, a citizen of the United States, residing at Leaksville, county of Rockingham, and State of North Carolina, have invented a new, original, and ornamental Design for a Combination Bench and Wardrobe, of which the following is a specification, reference being had to the accompanying drawings, forming part thereof.

In the drawing:

Figure 1 is a side elevation of my new design of combination bench and wardrobe, Figure 2 is a top plan view of the same, Figure 3 is an end elevation thereof, and Figure 4 is a similar view taken from the opposite end of the new design.

I claim:

The ornamental design for a combination bench and wardrobe, as shown.

WILLIAM B. KING.
